UNITED STATES PATENT OFFICE.

WALTER V. TURNER, OF WILKINSBURG, PENNSYLVANIA, ASSIGNOR TO THE WESTINGHOUSE AIR BRAKE COMPANY, OF PITTSBURG, PENNSYLVANIA, A CORPORATION OF PENNSYLVANIA.

ENGINEER'S BRAKE-VALVE.

No. 882,596.

Specification of Letters Patent.

Patented March 24, 1908.

Application filed June 23, 1905. Serial No. 266,587.

To all whom it may concern:

Be it known that I, WALTER V. TURNER, a citizen of the United States, residing in Wilkinsburg, in the county of Allegheny and 5 State of Pennsylvania, have invented a certain new and useful Improvement in Engineers' Brake-Valves, of which the following is a specification.

This invention relates to automatic fluid 10 pressure brakes, and more particularly to the engineer's brake valve, or means for controlling the supply of fluid under pressure to and its release from the train brake pipe.

In the present standard system of automatic air brakes, as is well known, there are 15 two kinds of brake applications, viz., service applications, produced by a slow or gradual discharge of air from the train pipe, causing the triple valves to move out only as far as 20 service position and supply air from the auxiliary reservoir through the graduating port to the brake cylinder, and quick-action or 25 emergency applications, produced by a more rapid or sudden reduction in train pipe pressure, which causes the operation of the so-called quick-action mechanism for effecting a 30 venting of the train pipe on each car, and so hastening the application by the well known serial action of the triple valves.

35 In making service applications of the brakes, all of the air which is released from the train pipe for the purpose of making the reduction is usually discharged at the brake valve at the forward end of the train, and in order to prevent undesired quick-action at such times, it is necessary that the train pipe discharge port for service applications be restricted to such size or capacity as not to permit a sufficiently rapid rate of reduction in 40 train pipe pressure as to cause the operation of the quick-action valve mechanism. The area or capacity of this discharge port is determined by conditions which prevail upon short trains of four or five cars, in which the 45 volume of train pipe pressure to be reduced is comparatively small and diminishes at substantially the same rate as that of the equalizing reservoir, consequently when the same capacity of discharge port must be used 50 for long trains, it will be evident that the time required for making a given reduction in pressure will be very much greater than on short trains.

55 It will also be apparent that a much larger port opening for the train pipe discharge may

be made upon a long train than upon a short one without danger of producing undesired quick-action, provided that the port is opened gradually, since, on account of the greatly increased volume of the train pipe the rate of 60 reduction which effects the triple valve mechanism will be much less at any given point in the train pipe.

In order to hasten the action of the brakes in service applications upon long trains, it is 65 therefore desirable that the train pipe discharge valve should open wider for a given reduction than upon short trains; or in other words, that the maximum area of the discharge port opening should be varied in 70 proportion to the length of the train pipe, and this is the principal object of the present invention. Various forms of apparatus may be devised for this purpose, but according to the preferred construction I provide a train 75 pipe discharge valve having a graduating port opening, and means, such as a movable abutment or piston, subject to the train pipe pressure for operating the valve, and a yielding resistance for retarding or opposing 80 the movement of the valve to the positions giving a larger area of port opening. Such a device may be conveniently embodied in connection with the usual equalizing piston and train pipe discharge valve of the standard 85 engineer's brake valve, and it is in this connection that I have illustrated my improvement in the accompanying drawing, which shows this portion of the engineer's brake valve in vertical section. 90

According to the drawing, the engineer's brake valve comprises the usual casing, having main reservoir connection 1, train pipe 2, and containing the usual rotary valve (not shown), chamber 3 connected with and forming part of the equalizing reservoir, equalizing piston 4, and train pipe discharge valve 5 controlling port 8, all of which may be of the ordinary standard construction of engineer's 95 brake valve, such as covered by prior Westinghouse patent No 557463 of March 31, 1896, which is well understood by all familiar with the art. 100

According to my improvement, the discharge valve is provided with a graduated 105 port opening by means of a projection below the face of the valve having two parts 6 and 7 of different degrees of taper. A yielding resistance device, such as a spring 9 and stem 10 is employed for retarding or opposing the 110

movement of the discharge valve to its extreme upper position, in which the port is open to its maximum area.

When a reduction is made in the equalizing reservoir for a service application of the brakes upon short trains of four or five cars, the equalizing piston opens the discharge valve to such point that the rate of reduction in the train pipe is substantially the same as in the equalizing reservoir, and the train pipe discharge valve then closes at nearly the same time that the handle of the rotary valve is turned to lap position to close the preliminary discharge from the equalizing reservoir, 10 as will be readily understood. Under these conditions there is very little difference in the pressures acting upon the opposite sides of the equalizing piston and the area of the discharge port opening must not be great enough to produce a quick-action or emergency application. The stem 10 is arranged to engage the upper wall of the chamber when the train pipe discharge valve port is open to the maximum area permissible for 20 short trains, so that the spring 9 exerts its influence to oppose the further opening movement of said valve, and as the difference in pressure acting on piston 4 during service reductions upon short trains is very small the 25 excess of train pipe pressure will not be sufficient to raise the valve higher or to compress the spring 9. Upon longer trains, however, when a service reduction is made from the equalizing reservoir, the pressure in 30 the train pipe does not diminish nearly as rapidly as in the equalizing reservoir owing to the much greater volume of train pipe, consequently a much greater excess of train pipe pressure accumulates beneath the piston 40 and operates to gradually compress the spring and move the valve higher or toward its extreme position of maximum port opening. It is evident that the longer the train the greater will be the excess of train pipe 45 pressure on the lower side of the piston over that of the equalizing reservoir during the period of making the reduction for a service application, and consequently the greater will be the movement of the piston in compressing the spring and opening the train pipe discharge port. By varying the taper of the valve projection or the area of the port opening corresponding to a certain movement of the valve, a much larger rate of discharge 55 may be produced as the spring is compressed, thereby reducing the time required to make a service application of a given degree of reduction on long trains. As the train pipe pressure diminishes and approaches that remaining in the equalizing reservoir, the spring will again expand and assist in returning the valve toward its closed position, to which it moves in the usual manner as the pressures equalize.

60 65 By means of mounting the resistance

spring on the equalizing piston my improvement may be readily applied to any standard brake valve by merely replacing one equalizing piston with another.

It will now be apparent that my improvement provides for varying the maximum area of the train pipe discharge port opening in proportion to the length or volume of the train pipe in making service applications whereby the time required for making reductions in train pipe pressure on long trains is greatly diminished, while at the same time the maximum port opening on short trains is limited to such area as will not produce a quick action or emergency application.

Having now described my invention, what I claim as new and desire to secure by Letters Patent is:

1. In a fluid pressure brake, the combination with a train pipe, a discharge valve for releasing fluid therefrom in making service applications a yielding resistance device for opposing the movement of the valve to its full open position and of means for automatically varying the maximum area of the discharge port opening in proportion to the length or volume of the train pipe.

2. In a fluid pressure brake, the combination with a train pipe, a discharge valve for releasing fluid therefrom in making service applications a yielding resistance device for opposing the movement of the valve to its full open position and of means operated by train pipe pressure for varying the maximum capacity of the discharge port opening for a given reduction in proportion to the volume of the train pipe.

3. In a fluid pressure brake, the combination with a train pipe, and a discharge valve for releasing fluid therefrom in making service applications, of a movable abutment subject to opposing fluid pressures for operating said discharge valve, and a yielding resistance means for opposing the movement of the valve to its position of maximum port opening.

4. In a fluid pressure brake, the combination with a train pipe, and a discharge valve for releasing fluid therefrom and having a graduated port opening, of a movable abutment subject to opposing fluid pressures for operating said discharge valve, and a spring for opposing the movement of the valve to its extreme open position.

5. An engineer's brake valve device comprising a chamber or reservoir, a train pipe discharge valve having a graduated port opening, a movable abutment subject to the opposing pressures of the train pipe and said chamber for operating said discharge valve, a manually operated valve for controlling the pressure in said chamber, and a yielding resistance means for opposing the movement of the discharge valve to its position of maximum port opening.

6. An engineer's brake valve device comprising a chamber or reservoir, a train pipe discharge valve, a movable abutment subject to the opposing pressures of the train pipe and said chamber for operating said discharge valve, a manually operated valve for controlling the supply of air from the main reservoir to the train pipe and for varying the pressure in said chamber or reservoir, and a spring for resisting the extreme opening movement of the train pipe discharge valve in service applications.

7. An engineer's brake valve device comprising an equalizing reservoir, a train pipe discharge valve having a graduated port opening and operated by the opposing pressures of the train pipe and said reservoir, a manually operated valve for controlling the pressure in said reservoir, and a yielding resistance for opposing the movement of the

discharge valve to its maximum open position.

8. An engineer's brake valve device comprising an equalizing reservoir, a train pipe discharge valve having a graduated port 25 opening, a piston subject to the opposing pressures of the train pipe and said reservoir for opposing said valve, a manually operated valve for controlling the pressure in said reservoir, said piston having a free preliminary 30 movement, and a spring for opposing the further movement of the piston in opening the discharge valve.

In testimony whereof I have hereunto set my hand.

WALTER V. TURNER.
